UNITED STATES PATENT OFFICE

2,566,361

METHOD OF MAKING CLOSED END SHOES

Benjamin F. Parrelli, Beverly, Mass., assignor to
United Shoe Machinery Corporation, Flemington, N. J., a corporation of New Jersey

Application June 11, 1948, Serial No. 32,313

12 Claims. (Cl. 12—142)

1

This invention relates to a novel method of making shoes, and more particularly shoes of the slip-lasted type.

It is the general object of this invention to produce a shoe of the slip-lasted type having a closed toe as good in appearance and wearing qualities as the toe of a conventionally lasted shoe and which, at the same time, may be manufactured with economy.

The method of this invention may be practised by cutting an upper, an upper lining and a sock lining each having a lasting allowance around the toe forward of the tip line, assembling the upper elements, stitching the upper elements to the sock lining rearwardly of the tip line of the shoe, inserting a last in the shoe, and then inserting a toe box between the lining and upper forward of the tip line. The shoe is then preferably presented to a toe forming machine to form the toe of the shoe, stitching is applied around the toe from tip line to tip line, and the lasting allowances are trimmed.

As will be illustrated, in order to complete the shoe, as when a shoe of the platform type is desired, the last is removed from the shoe, the front cover is attached, and the rear cover as well unless it has been earlier attached, the last is reinserted in the shoe, and the bottoming of the shoe is completed.

One modification of the invention will be described wherein the relasting process is eliminated.

In order that the exact nature of this invention may be better understood, reference is made to the accompanying drawings, wherein:

Fig. 1 is a perspective view of the cut and assembled upper;

Fig. 2 is an exploded perspective view showing the assembled upper and the sock lining;

Fig. 3 is a perspective view showing the attachment of the upper to the sock lining;

Fig. 4 shows the attachment of the rear cover to the shoe;

Fig. 5 shows a last inserted in the shoe and the portion of the upper and doubler forward of the tip line turned back from the lining;

Fig. 6 is a view showing the toe box;

Fig. 7 shows the toe box positioned over the lining ahead of the tip line;

Figs. 8 and 9 disclose the toe of the shoe positioned relative to the shoe support and wipers

2

of a toe forming machine, Fig. 8 showing a longitudinal section of the toe of the shoe and Fig. 9 a transverse section thereof;

Fig. 10 shows the stitching applied through the lasting allowances forward of the tip line and illustrates the trimming of the lasting allowances outside said stitching;

Fig. 11 shows the feed rollers, needle, thread and looper of a thread lasting machine with the toe of the shoe presented thereto;

Fig. 12 shows the shoe with the last removed and the front cover attached thereto;

Fig. 13 is an elevation of the completed shoe;

Fig. 14 is a cross-sectional view taken on the plane 14—14 of Fig. 13;

Fig. 15 is a plan view of the front cover as it may be made in practicing a modification of the invention;

Fig. 16 is a perspective view of a shoe showing the assembled upper attached to the sock lining rearward of the tip line, the rear cover attached and a front cover of the type disclosed in Fig. 15 attached to the shoe rearwardly of the tip line; and

Fig. 17 is a perspective view of a shoe made according to the modified process after the last has been inserted therein and the shoe presented to the toe forming and thread lasting machines.

Reference is made to Figs. 1 and 2 wherein the upper assembly is shown to include the upper 22, doubler 24 and lining 26 each of which may be composed of any suitable material. The upper, doubler and lining are each cut to have a seam allowance along their lower edges rearward of

the tip line which is defined by the points A and B, and ahead of the tip line the upper, doubler and lining are provided with the respective lasting allowances 22a, 24a and 26a.

The upper 22, doubler 24 and lining 26 are assembled to form the upper assembly, the upper 22 and doubler 24 being adhesively secured to one another over their entire adjacent surfaces, and the upper lining and doubler being similarly secured to one another rearward of the tip line AB. Stitching 28 is employed to fasten the upper elements together at the top of the upper, as well as to hold the upper edge of the quarter lining 30 in position, and the stitching 32 is employed to hold the front edge of the quarter lining 30 in the upper assembly, this stitching passing through the upper, doubler, lining and front end of the

quarter lining 30 and rear end of the upper lining 26. In the practice of this invention, the doubler may be omitted from the shoe and the upper lining is necessary only in the toe of the shoe.

The sock lining 34 is cut to have a seam allowance rearward of the tip line AB and a wider lasting allowance 34a forward of the tip line corresponding to the lasting allowance of the upper elements.

Having assembled the upper elements as described, the quarter lining 30 is separated from the doubler 24 and a counter 36, preferably of the mulled or activated type, is inserted in proper position in the pocket between the quarter lining 30 and doubler 24, and the quarter lining 30 is pressed against the inserted counter. The counter is preferably pre-cut so that it fits into the pocket between the quarter lining 30 and the doubler 24 with the bottom edge of the counter flush with the adjacent bottom edges of the quarter lining, doubler and upper.

Referring to Fig. 3, the upper assembly and sock lining 34 are then joined together as by stitching 38, employing a conventional type sewing machine, the stitching 38 extending from the tip point A rearwardly around the heel of the shoe and forwardly to the tip point B. This stitching passes through the upper, doubler, upper lining, counter, quarter lining and sock lining and securely attaches the upper assembly 20 to the sock lining 34 rearward of the tip line AB. It should be particularly noted, however, that the upper 22 and doubler 24 are not attached to the lining 26 and none of the upper elements are attached to the sock lining 34 forward of the tip line AB. In this stitching operation the stitching allowance on the sock lining 34 is turned downwardly into parallel position with respect to the stitching allowances of the upper elements to produce a generally depending rib 40 around the bottom of the shoe rearward of the tip line AB.

Turning now to Fig. 4, the next step in the process may be the attachment of the heel cover 42 to the shoe by means of the stitching 44 which extends from the area of the shank at one side of the shoe rearwardly around the heel and then forward to a point in the area of the shank on the other side of the shoe. The heel cover 42 is preferably fastened with its finished side adjacent to the exterior of the upper 22, and stitching 44 passes through the heel cover 42 and the rib 40 so that the inside portion of stitching 44 lies along the inner side of the rib.

As shown in Fig. 5, a last 46 is then inserted inside the shoe, the back seam (not shown) is properly aligned with the rear end of the last and, if desired, a tack 48 may be driven through the upper into the last 46 to hold the heel end of the shoe in proper position with respect to the last. Also, if desired, the sock lining may be pulled forward of the last by applying pincers to the lasting allowance 34a of the sock lining, and a tack (not shown) may be driven through the sock lining in the area of the shank into the last. These operations assist in shaping the still soft counter to the last and hold the heel of the shoe in proper position relatively to the last during the succeeding operations. The upper lining 26 may also be pulled forward of the last by the use of pincers.

The free toe ends of the upper 22 and doubler 24 are then turned back along the tip line AB, as also shown in Fig. 5, leaving the free toe end of the lining 26 in engagement with the toe end

of the last 46. A preferably mulled or activated toe box 50, such as is shown in Fig. 6, having a lasting allowance 50a corresponding to the other described lasting allowances and a skived rear margin 52b is then laid over the free uncovered toe end of lining 26, as shown in Fig. 7. The skived margin 52b of the toe box 50 is laid against the lining, and the toe box is cut in size and shape so that when its rear skived margin is laid along the tip line AB, the projecting edges of the box are flush with the corresponding edges of the lining. The previously turned back free toe portion of the upper and doubler are then turned forwardly and downwardly over the inserted toe box and pressed against the same.

The toe of the shoe on the last is then formed, and this step may be accomplished by presenting the shoe to a toe forming machine of the type disclosed in United States Patent No. 1,861,832 granted June 7, 1932 in the name of W. C. Baxter. As seen in Figs. 8 and 9 such a machine comprises the shoe support 54 which underlies the bottom surface of the sock lining 34 and lasting allowance 34a ahead of the tip line AB. The machine also comprises the wipers 56 having wiping surfaces 56a which engage the exterior surface of the toe of the upper 22 to wipe the same over the last 46. The wipers are preferably heated to cause the bonding agent of the toe box to set during the toe forming operation. When the machine is operated, the relative vertical movement of the plate 54 and wipers 56, the closing of the wipers 56 relative to the shoe, and the longitudinal relative motion of the shoe and wipers results in a toe smoothly and tightly wiped around the last, and the wiping operation also pulls the entire shoe upper forward relative to the last to shape the same to the last. The pressure applied to the toe elements during the wiping process causes a flow of the bonding agent of the toe box to impregnate the adjacent areas of the doubler and upper lining. The lasting allowances are firmly pressed together in the toe forming operation, and the lasting allowances of the upper and doubler, toe box and upper lining are securely bonded by the bonding agent of the lasting allowance of the toe box.

As illustrated, the feather line 46a of the last 46 is rounded off ahead of the tip line to permit the wipers 56 to wipe the upper elements into the beveled off corner of the last.

After the toe forming operation the shoe is left in the machine for the length of time required to perform the same operation on another shoe, during which time the formed toe of the shoe becomes set, and then the stitching 70 shown in Fig. 10 is accomplished. This stitching extends from the end of the tip line A around the toe of the shoe to the end of the tip line B and passes through the upper, doubler, toe box upper lining and sock lining. The stitching operation may be accomplished upon a thread lasting machine of the type disclosed in United States Patent No. 1,864,510, granted June 21, 1932, in the name of B. T. Leveque, a portion of such a machine being disclosed in Fig. 11 to which reference is now made.

In Fig. 11 it will be seen that the thread lasting machine includes an upper knurled feed roller 72 driven by shaft 74 and a lower knurled feed roller 76 driven by shaft 78.

The lasting allowances 22a, 24a, 50a, 26a and 34a of the upper, doubler, toe box, upper lining and sock lining are compressed by the feed rollers, and the stitching 70 is applied by the

needle 80 and looper 82 acting upon the thread 84. In this step of the process, the body of the shoe is preferably depressed with respect to the lasting allowances so that the needle passes through the elements being stitched at an angle with the needle passing inwardly of the shoe as it moves downwardly. The stitching is applied close to the beveled off feather line 46a of the last, which rounding off facilitates the placing of the stitching at the angle just described.

The provision of the described lasting allowances enable the toe forming machine to properly form the toe of the shoe, and provides means through which the thread lasting machine may stitch around the toe of the shoe.

After removal of the shoe from the thread lasting machine, the lasting allowances of the upper, doubler, toe box, upper lining and sock lining lying outside the stitching 70 are trimmed in any desired manner, as by the knife 71, although a trimming machine may be employed if desired. The tacks driven into the last through the heel and sock lining are next removed and the last is removed from the shoe.

Referring to Fig. 12, the front cover 92 is then attached to the shoe with its grain side in contact with the upper by stitching 94 which passes through the cover as well as the previously described depending rib 40 so that the inner portion of stitching 94 lies along the inner side of the rib, the lower edge of cover 92 being flush with the bottom edge of rib 40. Stitching 94, as shown in Fig. 14, is preferably inserted above seams 38 and 70, thereby somewhat reducing the interior volume of the shoe. As the cover 92 is being stitched around the toe of the shoe between the tip points A and B, a depending rib 40a which is a continuation of the previously-mentioned rib 40 is formed. This may be accomplished upon a standard sewing machine. Inasmuch as the toe box is at this stage in a semi-soft condition the stitching operation and formation of the rib may be accomplished with ease. The rear end of cover 92 on the side of the shoe shown in Fig. 12 slightly overlaps the adjacent forward end of cover 42 and cover 92 extends forwardly around the toe of the shoe and then rearwardly to a slightly overlapping position with respect to the end of the rear cover 42 on the other side of the shoe. The overlapping portions of the covers 42 and 92 are skived to eliminate undue thickness in the areas of the overlapping. If desired, the heel cover 42 may be attached to the shoe after the last has been removed therefrom, or a single cover completely encircling the shoe may be attached after the last is removed from the shoe.

As shown in Figs. 13 and 14 the last 46 is next forced into the shoe preparatory to performing the final operations in the manufacture thereof. It will be seen that to complete the shoe the platform 96 is placed in position, the shouldered margin of the platform underlying the previously described ribs 40 and 40a as well as the edges of the platform covers 42 and 92. The platform 96 is attached to the bottom of the sock lining 34 and to the lower edges of the ribs 40 and 40a by any suitable means, such as adhesive, and the rear cover 42 and front cover 92 are turned outwardly away from the upper 22 and downwardly covering the edge of the platform 96 and then the covers are turned inwardly under the margin of the platform 96, the coverstrips being attached to the engaged marginal surface of the platform by an adhesive. The sole 98 is then applied to the bottom of the shoe and cement attached to the

turned marginal portions of the covers 42 and 92. A heel 100 and top lift 102 are then attached to the shoe in the conventional manner. If desired, a fiber tuck or a shank and heel piece may be placed on the sock lining prior to the laying of the platform for receiving nails driven into the heel to hold the heel in proper position. In the event such a tuck is incorporated in the shoe the structure of the platform at the heel end of the shoe may be modified in any conventional manner.

The described process for manufacturing a closed-toe slip-lasted shoe is an economical process and produces a slip-lasted shoe having the qualities of a conventionally lasted shoe. The counter is securely positioned within the shoe by means of the bonding agent with which it is impregnated as well as by the stitching which passes through the sock lining, counter and quarter lining. The cutting of the upper and doubler, upper lining and sock lining with the described lasting allowances forward of the tip line of the shoe enables the toe-forming machine to smoothly wipe the upper elements around the last to produce a well formed and good looking toe having the wearing qualities of shoes having box toes made by conventional lasting methods. The heat imparted to the toe of the shoe by the toe-forming machine sets the toe box so that it does not creep while the shoe is being subsequently stitched in the thread lasting machine, and the subsequent stitching through the upper, doubler, toe box, lining and sock lining securely fastens the shoe elements at the toe of the shoe to insure retention of the qualities imparted to the shoe during the toe-forming process for the life of the shoe.

Although the invention of this application preferably includes the use of the toe-forming machine as previously described, the invention may be practiced by omitting the step of presenting the shoe to the toe-forming machine. In the event that this step is eliminated, after the toe box 50 has been laid over the lining 26 as shown in Fig. 7 and the doubler 24 and upper 22 have been turned downwardly over the inserted toe box, the shoe is presented to the thread lasting machine as shown in Fig. 11, and the thread lasting operation simultaneously forms the toe of the shoe and stitches through the lasting allowances as shown in Fig. 10. Also, if desired, the shoe may be presented first to the thread lasting machine and subsequently to the toe forming machine.

The process of this invention may be utilized in the manufacture of a closed toe, slip-lasted shoe without the necessity of performing the previously described relasting operation, in which case the process may be practiced as follows:

The upper 22, doubler 24, upper lining 26 and sock lining 34 are all cut as previously described, and the upper assembly is made as shown in Fig. 2. The counter 36 is inserted in the counter pocket and the upper assembly is stitched to the sock lining as previously described in connection with Fig. 3, and the heel cover 42 is also attached as shown in Fig. 4.

Referring now to Fig. 15 the front wrapper or cover 104 is cut to provide a lasting allowance 104a projecting from one side of the cover strip and extending from the tip points A' and B' of the cover which correspond to the previously described tip points A and B. The tip points A' and B' are separated by a distance of about $\frac{1}{8}$ " - $\frac{1}{16}$ " less than the distance from the tip point A to

the tip point B around the lower margin of the upper of the toe of the completed shoe. Referring to Fig. 16 the front cover is positioned relative to the upper 22 with the tip points A' and B' on the cover respectively overlying the tip points A and B on the upper, and the cover is attached to the shoe by stitching 106 which extends on each side of the shoe from the tip points A and A' and B and B' rearwardly to the ends of the cover 104, stitching 106 passing through the cover 104 and the depending rib 40 which, as previously described, is composed of the lower margins of the upper, doubler, lining and the margin of the sock lining. It should be particularly noted that the cover 104 is not stitched forward of the tip points A' and B', and consequently, the portion of the cover between these two points may be moved relative to the underlying parts of the shoe. Inasmuch as the distance from the tip point A' to the tip point B' on the wrapper 104 is slightly less than the distance from the tip point A to the tip point B around the lower margin of the upper, the lasting allowance 104a and unsewed section of the wrapper 104 will be somewhat to the rear of the position of the lasting allowance 22a of the upper, as shown in Fig. 16.

The last is next inserted in the shoe, the heel seam alined and the heel tack driven through the heel into the last. The sock lining is pulled forward and the tack driven through the sock lining in the area of the shank, all as previously described.

The free portion of cover 104 between the tip points A' and B', the lasting allowance 104a and the free portions of the upper 22 and doubler 24 between the tip points A and B are turned back, as previously described, and the mulled or activated toe box is laid over the lining 26. The turned back portions of the doubler, upper and wrapper 104 are then turned forward and pressed downwardly against the inserted toe box, the upper 22, doubler 24 and upper lining are all pulled forward of the last by the use of pincers, and the cover 104, between the tip points A' and B', is pressed downwardly, stretching the cover intermediate the tip points A' and B' to cause the cover to snugly fit around the toe of the last and to place the lasting allowance 104a over lasting allowance 22a of the upper.

The shoe is then presented to the toe-forming machine, as previously described, and the wipers 56 of the toe-forming machine press against the wrapper 104 and lasting allowance 104a and the previously described movements of the toe-forming machine form the toe of the shoe, as shown in Fig. 17, the lasting allowance 104a being pressed against the other described lasting allowances.

The shoe is then presented to the thread lasting machine, as previously described, and the stitching 108 is performed, this stitching passing through the lasting allowances 104a, 22a, 24a, 50a, 26a and 34a to securely fasten the wrapper 104, upper 22, doubler 24, toe box 50, lining 26, and sock lining 34 together around the toe between the tip points A and B.

The lasting allowances 104a, 22a, 24a, 50a, 26a and 34a are then trimmed as previously described, and the shoe is ready for the spotting of the platform and previously described subsequent operations necessary to complete the manufacture of the shoe.

The just-described alternative process makes it possible to manufacture a closed toe, slip-lasted shoe having the properties of a shop-

made by conventional lasting methods. The elimination of the relasting operation reduces the cost of manufacture even more than the first-described process, and the partial attachment of the front cover to the shoe prior to the toe-forming operation eliminates any direct contact between the wipers of the toe-forming machine and any exposed surface of the finished shoe, because the front cover is turned outwardly and downwardly in the subsequent completing of the shoe. Accordingly, damage to any finished surface of the shoe, and particularly to the upper, during the toe-forming operation is reduced to a minimum.

The process of this invention is applicable to shoes having a conventionally lasted heel, and when applied to such shoes the sock lining is stitched to the upper elements of the shoe, prior to the insertion of the last, from the tip points A and B rearwardly to the breast line. The toe of the shoe is completed as described herein, and the heel portion may be completed in any desired manner.

In view of the preceding disclosure, it will be appreciated that this invention provides a process for the manufacture of closed toe, slip-lasted shoes which is economical and which results in the production of a slip-lasted shoe having the appearance and wearing qualities, particularly in the toe, of a shoe produced by conventional lasting methods. Those skilled in the art will understand that certain of the steps set forth herein are not necessary to the practice of the invention, while on the other hand, additional steps may be included as the conditions under which the invention is practiced vary; furthermore, the essential steps of the invention need not be practiced in the exact sequence herein set forth, and other types of machines than those referred to herein may be employed.

All such variations in the practice of this invention are intended to be covered by the following claims:

I claim:

1. That improvement in methods of making shoes which includes the steps of providing an upper having a lasting allowance forward of the tip line thereof, providing a sock lining having a lasting allowance corresponding to the lasting allowance of the upper, providing a lining in at least the toe portion of said upper, uniting the upper and sock lining rearward of the tip line, inserting a last in the shoe, inserting a toe box between the upper and its lining, and uniting the upper and sock lining forward of the tip line by fastenings extending through said lasting allowances near the edge of the last.

2. That improvement in methods of making shoes which includes the steps of providing an upper having a lasting allowance forward of the tip line thereof, providing a sock lining having a lasting allowance corresponding to the lasting allowance of the upper, providing a lining in at least the toe portion of said upper, uniting the upper and sock lining rearward of the tip line, inserting a last in the shoe, inserting a toe box having a lasting allowance between the upper and upper lining, fastening together the upper, toe box and sock lining forward of the tip line near the edge of said last, and trimming the lasting allowances of the toe box, upper and upper lining outside said fastenings.

3. That improvement in methods of making slip-lasted shoes which includes the steps of providing an upper and a sock lining each having a

lasting allowance forward of the tip line and a seam allowance rearward of the tip line, providing a lining in at least the toe portion of said upper, uniting the upper and sock lining by stitching along the said seam allowances, inserting a last inside the shoe, inserting a toe box between the upper and its lining, fastening together the upper and sock lining near the edge of the last forward of the tip line thereof, trimming the lasting allowances outside said last-mentioned fastenings, removing the last from the shoe, attaching a cover strip around the toe of the shoe by stitching through the margins of the cover strip, upper, toe box, upper lining and sock lining, reinserting the last in the shoe, laying a platform sole underneath the sock lining, lasting the cover in over the bottom margin of the platform sole, and attaching an outsole.

4. That improvement in methods of making shoes which includes the steps of providing an upper having a lasting allowance forward of the tip line thereof, providing a sock lining having a lasting allowance corresponding to the lasting allowance of the upper, providing a lining in at least the toe portion of said upper, uniting the upper and sock lining rearward of the tip lines of the same, inserting a last in the shoe, inserting a toe box between the upper and its lining, fastening together the upper and sock lining near the edge of the last forward of the tip line, trimming the lasting allowances outside said stitching, removing the last from the shoe, and attaching a cover strip around the toe of the shoe by fastenings extending through the margins of the cover strip, upper, toe box, upper lining and sock lining.

5. That improvement in methods of making slip-lasted shoes which includes the steps of providing an upper having a lasting allowance forward of the tip line thereof, providing a sock lining having a lasting allowance corresponding to the lasting allowance of the upper, providing a lining in at least the toe portion of said upper, uniting the upper and sock lining rearward of the tip lines of the same, inserting a last in the shoe, inserting a toe box between the upper and its lining, forming the toe of the shoe, inserting a line of fastenings to unite the upper and sock lining near the edge of the last forward of the tip line, trimming the lasting allowances outside said line of fastenings, removing the last from the shoe, attaching a cover strip around the toe of the shoe by stitching through the margins of the cover strip, upper, toe box, upper lining and sock lining, reinserting the last in the shoe, laying a platform sole underneath the sock lining, lasting the cover in over the bottom margin of the platform sole, and attaching an outsole.

6. That improvement in methods of making shoes which includes the steps of providing an upper and a sock lining each having a lasting allowance forward of the tip line, providing a lining in at least the toe portion of said upper, uniting the upper and sock lining rearward of the tip line, positioning a cover around the toe of the shoe and attaching the cover to the shoe rearward of the tip line, inserting a last in the shoe, inserting a toe box between the upper and its lining, and conforming the toe of the shoe to the last.

7. That improvement in methods of making shoes which includes the steps of providing an upper and a sock lining each having a lasting allowance forward of the tip line, providing a lining in at least the toe portion of said upper,

uniting the upper and sock lining rearward of the tip line, positioning a cover around the toe of the shoe and attaching the cover to the shoe rearward of the tip line, inserting a last in the shoe, inserting a toe box between the upper and its lining, conforming the toe of the shoe to the last, and uniting the cover, upper and sock lining forward of the tip line by inserting fastenings through said cover and the lasting allowances of the upper and sock lining near the edge of the last.

8. That improvement in methods of making shoes which includes the steps of providing an upper and a sock lining each having a lasting allowance forward of the tip line, providing a lining in at least the toe portion of said upper, uniting the upper and sock lining rearward of the tip line, providing a cover having a lasting allowance along one side thereof and positioning the cover around the toe of the shoe with the lasting allowance of the cover ahead of the tip line of the shoe, attaching the cover to the shoe rearward of the tip line thereof, inserting a last in the shoe, inserting a toe box between the upper and its lining, and conforming the toe of the shoe to the last.

9. That improvement in methods of making shoes which includes the steps of providing an upper and a sock lining each having a lasting allowance forward of the tip line, providing a lining in at least the toe portion of said upper, providing a cover having a lasting allowance along one side thereof and positioning the cover around the toe of the shoe with the lasting allowance of the cover forward of the tip line of the shoe, uniting the upper, sock lining and cover rearward of the tip line, inserting a last in the shoe, inserting a toe box between the upper and its lining, conforming the toe of the shoe to the last, joining together the cover, upper, toe box and sock lining by fastenings inserted through the same near the edge of the last, and trimming the lasting allowances of the cover, upper, toe box and sock lining outside said fastenings.

10. That improvement in methods of making shoes which includes the steps of providing an upper having a lasting allowance at one end thereof, providing a sock lining having a lasting allowance corresponding to that of the upper, uniting the upper and sock lining from the lasting allowances toward the other end of the shoe, inserting an end stiffener in the end of the shoe having the said allowances, and uniting the upper and sock lining by inserting fastenings extending through said allowances near the edge of a last placed in the shoe.

11. That improvement in methods of making shoes which includes the steps of providing an upper, lining and sock lining each having lasting allowances at an end of the shoe, positioning a cover about said end of the shoe, securing portions of the cover at the shank to the upper and sock lining at opposite sides of the shoe leaving the central portion of the cover free, inserting an end stiffener in that end of the shoe, drawing the free portion of the cover down about the end of a last in the shoe, and securing the cover, upper, lining and sock lining together about that end of the shoe.

12. That improvement in methods of making shoes which includes the steps of providing an upper and upper lining having lasting allowances at an end thereof, providing a sock lining and a cover having lasting allowances corresponding to those of the upper, uniting the upper, sock lin-

ing and portions of the cover at each side of the shank portion of the shoe leaving the central portion of the cover free and extending about the end of the shoe above the bottom thereof, inserting an end stiffener between the upper and lining, working the cover down into position about the end of the shoe, and securing together the yet-unsecured portion of the cover, upper and sock lining about the end of the shoe in which a last has been placed.

BENJAMIN F. PARRELLI.
